(Cl. D81—25)

Fig. 2.

FIG. 1 is a front perspective view of a counter-top range and exhaust combination embodying our new design with the cover in closed position.

FIG. 2 is a view similar to FIG. 1 with the cover in open position.

The dominant features of our design reside in the portions shown in full lines. The right side is substantially the same as the left side shown.

We claim:

The ornamental design for counter-top range and exhaust combination, as shown and described.
